UNITED STATES PATENT OFFICE.

ROBERT ALEXANDER KEMP, OF LONDON, ENGLAND.

COMBINED ORGAN AND PIANO.

SPECIFICATION forming part of Letters Patent No. 352,060, dated November 2, 1886.

Application filed November 4, 1885. Serial No. 181,847. (No model.) Patented in England September 7, 1885, No. 10,574.

To all whom it may concern:

Be it known that I, ROBERT ALEXANDER KEMP, musical-instrument maker, a subject of the Queen of Great Britain, and a resident of London, England, have invented new and useful Improvements in and Relating to Combined Reed and String Musical Instruments, (for which I have obtained a patent in Great Britain, No. 10,574, bearing date September 7, 1885,) of which the following is a specification, reference being had to the accompanying drawings.

My invention relates to musical instruments in which the mechanism of an ordinary piano-forte is combined with that of a reed-organ.

The objects of the said invention are to improve the quality of tone and obtain a compact and convenient form and arrangement of the parts of such instruments.

My improvements are applicable to upright or grand piano-fortes, either in the course of or subsequently to their construction, and also to old or existing instruments. In the case of ordinary upright piano-fortes the said improvements can be applied without increasing the size of the instrument or altering its general external appearance.

In the accompanying drawings I have shown how my improvements may be conveniently and advantageously applied to an upright piano-forte.

Figure 1 is a vertical transverse section of the instrument. Fig. 2 shows a portion of Fig. 1 drawn to an enlarged scale. Fig. 3 is a plan of the air-chamber of the reed apparatus with some of the parts removed. Fig. 4 is a front elevation illustrating various details of construction. Fig. 5 is a plan showing parts of the reed-operating mechanism. Fig. 6 is a vertical longitudinal section, drawn to an enlarged scale, of the tremolo, hereinafter described.

a indicates the frame or case of the instrument. *b* is the sound-board. *cc* are the springs. *d d* are the keys. These parts and the piano-forte action may be of any well known or suitable construction.

e indicates the bellows of the organ, which in the instrument shown are exhaust-bellows.

f is the air-chamber.

g is one of a series of free reeds, secured in any suitable manner upon the top of the air-

chamber *f*, in front of the sound-board *b*. Each reed is arranged above an aperture in the top of the air-chamber and within a reed chamber 55 or cell, *h*. A valve, *i*, is hinged to the top of the air-chamber beneath each of these apertures, and is acted upon by a spring, *i'*, which tends to keep the said valve closed. These valves are arranged in combination with the 60 mechanism hereinafter described, and with the keys *d*, so that either of the said valves can be opened by depressing the corresponding key. This mechanism is, however, so arranged that the organ can be either connected with the keys *d* or thrown out of action, as desired. In combination with each valve *i*, I provide a plunger, *k*, and a bent or cranked lever, *l*, one end of which, when the parts are in the position shown, bears upon 65 the top of the said plunger. A similar plunger, *m*, is provided beneath each key *d*, and bears upon the other end of the corresponding lever, *l*. The plungers *k m* are fitted to slide up and down in suitable guides in a well-known manner. The bent levers *l* are more clearly shown in Fig. 5. They consist of pieces of wire bent to the required shape, and fitted in suitable bearings in the lugs or blocks *l'*, attached to the rail or table *n*. This rail or table is hinged or pivoted at *n'* to the top of the air-chamber *f*, and under normal conditions occupies the position indicated by dotted lines 70 in Fig. 1, the organ mechanism being unconnected with the keys *d*. The said rail or table is shown in full lines in this figure in the position which it occupies when the organ mechanism is connected with the keys *d*. It is raised to and supported in this position by the following means, viz: A series of levers, 75 *o*, are pivoted at *o'* to the front of the air-chamber *f*, and are connected by a rod or link, *o''*. A knee-lever, *p*, is pivoted at *p'*, beneath the key-board, and is made with a fork at one end, which engages with the central lever, *o*. By 80 moving the lever *p* in one or the other direction the rail or table *n* can be very readily raised or lowered, as required.

When the rail or table *n* is in its raised position, the plungers *m* are in contact with the keys *d*, as shown in Figs. 1 and 2, and if one of the said keys is depressed the corresponding valve, *i*, will be opened by means of the corresponding plungers, *k m*, and lever *l*. When,

however, the rail or table *n* is lowered, the keys *d*, when they are depressed, will not touch the plungers *m*. Therefore the key-board of the piano-forte will be in its normal condition and 5 entirely free from or independent of the organ mechanism.

The air-chamber *f* is made with two apertures, *f'* *f''*, to permit the passage of air from the said chamber to the bellows *e*. Over the 10 aperture *f'* is fixed a box or casing, *q*, having an aperture, *q'*, beneath which is arranged a tremolo, *q''*, of the kind usually employed in organs. When this tremolo is in operation, it produces a wave-like motion of the air in front 15 of the sound-board. A tremolando is thus imparted to both strings and reeds; but the tones of the strings and reeds are so blended that it is sometimes impossible to decide which tones are heard—that is to say, whether the sounds 20 heard are produced by the vibrations of the strings or by the vibrations of the reeds.

The tremolo is governed or controlled by the following means, viz: A valve, *r*, is hinged or pivoted to the air-chamber over the air-passage *f''*. A rod, *r'*, is coupled to the said valve, and is arranged to be raised and lowered to open and close the valve by means of a bent wire or lever, *r''*, operated by a knee-lever, *p*. By opening the said valve and permitting the 25 air to pass to the bellows through the passage *f''* the vibratory motion of the tremolo can be 30 instantly arrested when not required.

The swell consists of a valve or swell-shutter, *s*, arranged to be opened and closed by 35 means of a bent wire or lever, *s'*, operated by a knee-lever, *p'*.

t is a pedal or foot-lever, which is connected with the bellows *e* by a cord or chain, *t'*, passing over a wheel or pulley, *t''*, and which is 40 preferably placed on the right-hand side of the ordinary piano-forte pedals. The bellows are provided with springs *e'* *e''*, which by their reaction assist in operating the said bellows.

In using the instrument as a simple piano-forte, it is only necessary to play as on an ordinary instrument, holding down the soft or 45 loud pedal at pleasure. In using it as an organ or harmonium without the piano-forte accompaniment, the left-hand or soft pedal must 50 be held down, the knee-lever *p* pushed to the left into the position indicated in Figs. 4 and 5, and the pedal *t* worked like the ordinary blow-levers of an organ. Then by playing softly, any legato or sustained music can be ex- 55 ecuted without the sound of the strings being audible. In using the instrument as a piano-forte and organ combined, a melody may be sustained on the reeds and a pianissimo or soft 60 accompaniment produced at the same time from the strings. Both strings and reeds can thus be used without making any change in the stops or pedals. The tones of the piano-forte can in this case be augmented and sustained or prolonged by the continued vibration 65 of the reeds, and the tones of the organ and those of the piano-forte will, as above stated, be so intermingled or blended that it will be

difficult, if not impossible, to distinguish the sounds of the reeds from those of the strings, notwithstanding the fact that in one case the 70 sounds are produced by percussion, while in the other case they are produced by wind. By releasing the soft pedal the piano-forte can be made to dominate the organ. The center 75 pedal is the ordinary-forte pedal for raising the dampers from the strings.

The reeds which I prefer to use for the purpose of my invention are those commonly known as "American organ-reeds," and I prefer to use exhaust-bellows, as shown; but where 80 greater power of tone is required I use the free reeds, termed "harmonium-reeds," the action of the bellows for which must be the reverse of that above indicated—that is to say, the air must be forced outward or expired instead of 85 being drawn inward or inspired. These two forms of reeds and bellows are equally applicable for the purpose of my invention, the only difference being an increased power and a more reedy quality of tone in the case of the 90 harmonium-reeds and the expiratory bellows. In both cases the sound-waves from the reeds are directed against the sound-board of the piano-forte, thereby improving the quality of tone of the reeds, and, as above stated, prolonging 95 the vibrations of the strings.

The reed-organ may be of any compass from one to eight octaves, according to the extent of the key-board or the will of the maker.

The chief advantages afforded by my invention are as follows, viz: The perfect blending of the tones of the organ with those of the piano-forte obtained, as above described, by placing the reeds in front of and across the sound-board; also, the prolongation of the 105 sounds produced by the piano-forte beyond their ordinary duration, by the continued vibration of the springs in sympathy with the vibratory action of the reeds; also, the power to produce a tremolando in the tone of the 110 piano-forte in addition to that obtained on the organ by reason of the transmission of vibratory motion from the reeds and bellows to the sound-board and strings; also, the power to apply reed-organs to upright piano-fortes without 115 increasing the size of the instrument or altering its external appearance.

It is obvious that the construction of the instrument may be somewhat varied without departing from the nature of my said invention. 120

What I claim is—

1. The combination, with a piano-forte, of the bellows *e*, the air-chamber *f*, having the apertures *f'* *f''*, and the tremolo *q''*, the reeds *g*, and the reed-cells *h*, the valves *i*, and springs *i'*, the plungers *h m*, and levers *l*, mounted upon the pivoted rail or table *n*, and means for raising and lowering the said rail or table to put the organ mechanism in or out of action, all substantially as and for the purpose set forth. 125

2. In a combined reed and string musical instrument, the combination of the sound-board *b*, the strings *c*, the air-chamber *f*, reed-cells *h*, reeds *g*, valves *i*, having springs *i'*, 130

cranked levers *l*, plungers *k m*, and keys *d*, substantially as described.

3. The combination, with the strings *e*, reeds *g*, air-chamber *f*, and valves *i*, of the table *n*, 5 pivoted to the top of the air-chamber and provided with blocks *l'*, the levers *l*, plungers *k m*, and keys *d*, substantially as described.

4. The combination, with the strings *e*, reeds *g*, valves *i*, and keys *d*, of the table *n*, levers *o*, connecting rod or link *o'*, forked knee-lever *p*, levers *l*, and plungers *k m*, substantially as described.

5. The combination of the bellows *e*, the air-chamber *f*, having apertures *f' f''*, the casing 15 *q*, having an aperture, *q'*, the tremolo *q''*, valve *r*, rod *r'*, and levers *r' p'*, substantially as described.

6. The combination, with a piano-forte, of the bellows *e*, the air-chamber *f*, having the apertures *f' f''*, and the tremolo *q''*, the reeds *g*, 20 and reed-cells *h*, the valves *i*, and springs *i'*, the plungers *k m*, and levers *l*, mounted upon the pivoted rail or table *n*, and means for raising and lowering the said rail or table, all substantially as and for the purposes set forth. 25

In testimony whereof I have hereunto signed my name in the presence of two subscribing witnesses.
